UNITED STATES PATENT OFFICE.

ALBERT H. OVERMAN, OF NEWTON, ASSIGNOR TO THE OVERMAN WHEEL COMPANY, OF BOSTON, MASSACHUSETTS.

VELOCIPED.

SPECIFICATION forming part of Letters Patent No. 398,533, dated February 26, 1889.

Original application filed December 13, 1886, Serial No. 221,368. Divided and this application filed January 16, 1889. Serial No. 298,491. (No model.)

To all whom it may concern:

Be it known that I, ALBERT H. OVERMAN, residing at Newton, in the county of Suffolk and State of Massachusetts, have invented 5 certain new and useful Improvements in Velocipedes; and I do declare the following to be a full, clear, and exact description of the same, reference being had to the accompanying drawings, which form a part of this specification. 10

This case is presented as a division of the application filed December 13, 1886, by the same applicant, and serially numbered 221,368, and is designed to cover so much of the invention 15 disclosed in that application as is not involved in a pending interference, in which the same has been placed and is properly divisional matter.

My invention relates to an improvement in 20 velocipedes, the object being to adapt them to absorb vibration, and thus increase their comfort and durability.

With these ends in view my invention consists in a wheel-fork composed of independent 25 bowed springs, and in certain details of construction, as will be hereinafter more fully described, and pointed out in the claims.

In the accompanying drawings, Figure 1 is 30 a view in side elevation of my improved spring wheel-fork, in combination with a steering-wheel and steering-rod of a velocipede. Fig. 2 is a view of such parts in front elevation with the wheel in broken lines, and Fig. 3 is an enlarged detached perspective view of 35 the spring wheel-fork.

As herein shown, my improved spring wheel-fork is composed of four heavy independent bowed spring-rods, H, separated at each end and placed side by side with a sufficient space 40 between the inner rods for the wheel G to run in, the rods on the same sides of the wheel being substantially parallel with each other. By preference, and as shown, the rods are so bowed as to bring the rearwardly- 45 inclined steering-rod A into line with the center of the wheel. The upper ends of the rods are attached at equal distances apart to a horizontal cross-head, I, located at a point outside of the rim of the wheel and rigidly 50 secured to the lower end of the steering-rod

A, which is mounted in the steering-head D, located at the forward end of the reach F of the vehicle-frame, with which the upper ends of the rods are thus connected. The lower ends of the rods have eyes J, adapted to be 55 slipped over the extended ends K of the wheel-axle L. A transverse brace, N, of any suitable construction, is employed for tying the rods together. As shown, it is located about midway the length of the rods and curved 60 outward, as at M, to escape the rim of the wheel. This brace M may, however, be dispensed with, if desired, without departing from my invention. Short tubes C', located upon the extended ends K of the axle, are 65 interposed between the eyes J, formed at the lower ends of the spring-rods H, and preserve the lower ends of the said rods in their relations to each other, the said eyes and tubes being held upon the axle by nuts D'. 70

A spring wheel-fork, made as described, responds readily to vertical impressions and absorbs vibration, so as to not only promote the comfort of the rider, but also prolong the life of the machine by saving it from much 75 wrenching and straining. Although cushioning vertically, as described, the fork is protected against twisting or other deflection by the location of its rods side by side, and by having common connections, respectively, for 80 their upper and lower ends, whereby they brace each other laterally.

My improved spring wheel-fork is not limited to use with a steering-wheel of a velocipede, but may be applied to other wheels of 85 such vehicles. If desired, more than four rods may be employed in the fork, and their curvature and relative arrangement may be modified as becomes expedient.

I would have it understood that I do not 90 limit myself to the exact arrangement of parts shown and described, but hold myself at liberty to make such changes and alterations as fairly fall within the spirit and scope of my invention. 95

Having fully described my invention, what I claim as new, and desire to secure by Letters Patent, is—

1. In a velocipede, a wheel-fork composed of four or more bowed springs placed side by 100

side, with a space between the inner springs for the wheel to run in, substantially as set forth.

2. In a velocipede, the combination, with a wheel-fork composed of independent bowed springs, separated at each end, and each secured at one end to a cross-head common to them all, of a wheel having its axle extended at each end for the attachment of the other ends of the said springs, substantially as set forth.

3. In a velocipede, the combination, with a rearwardly-inclined steering-rod and a steering-wheel, of a bowed spring-fork composed of four or more independent springs connected with the lower end of the rod and with the wheel-axle, and curved, substantially as shown, so as to bring the rod virtually in line with the center of the wheel, substantially as set forth.

4. In a velocipede, the combination, with a steering-rod having a cross-head rigidly se-

cured to its lower end, of a steering-wheel having the ends of its axle extended, and a spring wheel-fork composed of four or more bowed springs placed side by side with a space between the inner rods for the wheel to run in, and having their upper ends rigidly secured to the said cross-head, and their lower ends provided with eyes adapting them to be slipped over the extended ends of the wheel-axle, substantially as set forth.

5. In a velocipede, a wheel-fork composed of bowed spring-rods and a transverse brace tying such rods together, substantially as set forth.

In testimony whereof I have signed this specification in the presence of two subscribing witnesses.

ALBERT H. OVERMAN.
